MARK.

PERCUSSIVE HAND TOOL.

Application filed January 3, 1924, Serial No. 684,262, and in Germany January 17, 1923.

This invention relates to percussive hand tools of the kind in which a striking piece or tup is movable in a casing and reciprocated by the action of one or more rotating flyweights mounted on the tup, the flyweights being preferably driven from an electric motor mounted as a unit with the tup casing.

The object of the present invention is to construct a percussive hand tool of the character described which will have a striking force sufficient for a heavy chisel or for rough riveting or like heavy work, without the tool being unwieldy, that is to say, without being of excessive weight or overall dimensions.

Heretofore, in percussive hand tools of the character described, it is usual for the tup to make one blow for each revolution of the flyweight, but it is found that at certain speeds above a certain critical value, the number of impacts of the tup becomes a fraction of the number of revolutions of the flyweight, that is to say, the tup makes one blow for each two, three, four or more revolutions of the flyweight, the number of blows per unit of time decreasing as the speed of the flyweights is increased. Not only does the number of impacts of the tup decrease; it has been found that the force of the blow increases with the decrease in the number of blows of the tup so that, by increasing the speed at which the flyweights rotate, the strength of the blow can be materially increased without increasing the weight of the tool. It has also been found that in the interval between the actual working or striking strokes of the tup, the latter carries out idle strokes which do not reach the tool, the length of the working stroke being materially increased. It is therefore a further object of this invention to enable the increased striking force to be obtained without appreciably increasing the overall length of the tool.

According to the present invention therefore, a percussive hand tool of the character described comprises driving or change-speed gear adapted to drive the flyweights at such a speed that the number of impacts of the tup becomes a fraction of the number of revolutions of the flyweights, and driving and driven shafts splined together so as to telescope within each other to compensate

for the increased length of the reciprocations of the tup.

In order that the invention may be more clearly understood, reference will be hereinafter made to the accompanying explanatory drawings whereon Fig. 1 is a view partly in longitudinal section and partly in elevation of one form of percussive hand tool according to this invention. Figs. 2 and 3 are diagrams hereinafter referred to and Fig. 4 is a detail sectional view of a modified construction.

Referring to Fig. 1 of the drawings, A is an electric motor mounted as a unit with the casing J which contains a striking piece or tup K on which are rotatably mounted the flyweights G. The motor A drives the flyweights G through a spindle E and gearing B. A spring H acts on the tup K in known manner to store up energy and exert a unidirectional force on said tup. Under the combined action of the rotating flyweights G and pressure of the spring H, the tup K exerts a blow which is transmitted to the tool T through a flexible diaphragm L in known manner.

Referring now to Fig. 2 which is a curve representing the position of the tup as a function of the time when the number of blows made by the tup is only one third the number of revolutions of the flyweights: —it will be seen that at 1 the tup begins to rise and at 2 has reached its highest position during the first revolution of the flyweights. At 3 the tup begins its second upward stroke although it has not returned to its original position on line 1—7. This is due to the fact that the flyweights have revolved so far during the interval that their centrifugal force overcomes the downward impulse of the tup. At 4 the tup has reached its highest position in the second revolution of the flyweights and at 5 it is again swung back by the centrifugal force of the flyweights before it has completed its downward stroke. It then reaches its highest position at 6 and finally discharges its energy in the blow at 7. The idle strokes 3 and 5 are of indirect utility, because they result in the effective stroke of the tup from 6 to 7 taking place in a shorter space of time and at a greater velocity, dependent on the increase in the number of idle strokes. Moreover the force of impact is proportional to

the square of the velocity. This may also be expressed by stating that the number of idle strokes increases the inclination of the curve 6—7 which represents the working stroke, making its inclination steeper than when one blow takes place for each revolution of the flyweights. Without going deeply into the complex theory of the physical operations the accumulation of energy 10 may be explained as follows:—The impulse of the working or effective stroke (mean striking force multiplied by the time of the blow) is equal to the rearward impulse on the casing or operator's hand. The time of 15 the rearward impulse increases according to the number of idle strokes and consequently the impulse inherent in the blow also increases.

It will be apparent from the foregoing 20 remarks that the force of impact of the tup can be multiplied considerably without increasing the weight of the tool.

It is however essential that the speed of the flyweights should be kept fairly constant. 25 This will be apparent from the curve I of Fig. 3 wherein the force of impact in mkg. (meterkilograms) is represented for different revolutions (per unit of time) of the flyweight and wherein A represents one 30 blow per revolution, B one blow for two revolutions and C one blow for each three revolutions of the flyweights and wherein a' , a^2 and a^3 represent different revolutions per unit of time of the flyweights where no impact takes place. In order to ensure steady 35 operation when an electric motor is employed, it is necessary that the motor should have a rapidly decreasing speed characteristic (torque as a function of the number of 40 revolutions). A shunt motor which has a constant speed, might, for example, run at the speed indicated by one of the points a' , a^2 or a^3 where the impact of the tup is zero. It will therefore be preferable to employ 45 a series-motor or a shunt motor wherein a decreasing speed characteristic is produced by compounding or inserting a resistance in the armature circuit. In the case of induction motors it would be necessary to provide 50 a comparatively high rotor resistance.

The torque curve II of Fig. 3 intersects the curve I at b and it will therefore be seen that the operation of the tool at this point would be steady and that the flyweights 55 should therefore preferably be run at a speed of a' revolutions per unit of time. The speed of the motor may be varied to regulate the timing of the tup impacts.

The increase in the force of impact of 60 the tup however also involves a longer stroke and it would be necessary therefore to increase the length of the tool casing. In order to obviate this necessity the motor or driving shaft may be made hollow to receive 65 and guide the driven spindle of the gear-

ing, thus reducing the overall length of the tool and also doing away with a special bearing for the gear spindle, as the motor shaft will serve to support the gear spindle. Such a construction is shown in Fig. 1 70 wherein the motor shaft W is hollow and keyed to the hub D of a flange or disc M which is integral with or secured to a casing or box having a cylindrical wall N and a lower disc or bottom O. A sleeve P on 75 a spindle E which passes through the box or casing N, is resiliently connected to the box N by a resilient transmission device, such as a spring Y or other resilient coupling. The sleeve P is splined on the spindle E by means of a key or feather working in the groove E' in the spindle E and the spindle extends into the hollow motor shaft W, which forms a bearing for the spindle E. It will be understood that the motor 80 shaft W rotates the box or casing N and that the rotary motion is resiliently transmitted to the sleeve P through the spring Y. The sleeve P thus rotates the spindle E which carries one of the pinions B, whilst the spindle E is free to reciprocate in the hollow motor shaft W under the reciprocation of the tup and its gearing B. Fig. 1 shows the spindle E almost up to the end of the 85 socket in the hollow shaft W.

Fig. 4 shows a modification wherein rollers S carried in a roller cage H are inserted between the flyweights G and their journal pins F. It will of course be understood that balls or other anti-friction devices 90 may be used in place of the rollers. This construction facilitates the operation of the tool by reducing the frictional resistance to revolution of the flyweights at a high 95 speed.

Claims—

1. A percussive hand tool of the character described, comprising a casing, an electric motor mounted as a unit therewith, a shaft driven by said motor, a tup movable in said 110 casing, a flyweight rotatably mounted on the tup, a driven shaft splined to the aforesaid shaft, whereby said shafts are telescopic, and gearing interposed between said driven shaft and flyweight whereby the number of impacts of the tup becomes a fraction of the 115 number of revolutions of the flyweight.

2. A percussive hand tool of the character described, comprising a casing, a tup movable therein, a flyweight rotatably mounted on the tup, an electric motor mounted as a unit with the casing, a hollow motor shaft, a spindle telescoping in said shaft but rotatable therewith and gearing interposed between 120 said spindle and flyweight such that the number of impacts of the tup becomes a fraction of the number of revolutions of the flyweight.

3. A percussive hand tool of the character described comprising a casing, a tup mov- 125

able therein, a flyweight rotatably mounted on the tup, an electric motor mounted as a unit axially within said casing, a driving shaft, connections between said motor and said shaft, gearing between said shaft and flyweight such that the number of impacts of the tup becomes a fraction of the number of revolutions of the flyweight and a resilient transmission device interposed between the driving shaft and the flyweight. ¹⁰ In testimony whereof I hereunto affix my signature.

RUDOLF GOLDSCHMIDT.
